UNITED STATES PATENT OFFICE.

RODOLPHE CHRISTESEN, OF NEW BRITAIN, CONN., ASSIGNOR TO THE RUSSELL & ERWIN MANUFACTURING COMPANY, OF SAME PLACE.

DESIGN FOR DOOR-ESCUOTCHEONS.

SPECIFICATION forming part of Design No. 11,620, dated February 3, 1880.

Application filed December 22, 1879. Term of patent 7 years.

To all whom it may concern:

Be it known that I, RODOLPHE CHRISTESEN, of New Britain, in the county of Hartford and State of Connecticut, have invented a new and useful Design for Escutcheons for Doors; and I do hereby declare that the following specification, taken in connection with the accompanying illustration, forming a part of the same, is a full, clear, and exact description thereof.

10 The design hereinafter described is adapted to ornamental escutcheons for doors, and possesses the characteristic feature of being in the Japanese style of ornament. As shown in the accompanying illustration, it possesses an architectural appearance, and may be described as representing a balcony, A, supported upon corbels a, and surmounted by an ornamental roof, B, supported upon columns b. The balcony is occupied by a human figure, C, and from its rail depends a ring, c, which is perforated to admit the key of a lock. Upon the roof portion B is placed an ornamental rosette, D, which is adapted to receive the shank and spindle of a knob. The extreme upper portion is in the form of a gable, the face of which is 25 ornamented, the slopes and apex, respectively, being provided with barge-boards E and a finial, e.

What I claim, and desire to secure by Letters Patent, is—20 The design for an escutcheon representing a roofed balcony ornamented in the Japanese style, and occupied by a human figure, substantially as described and shown.

RODOLPHE CHRISTESEN.
